R. RODER

CAN END FOLDING MACHINE

Filed Dec. 24, 1925

UNITED STATES PATENT OFFICE.

RICHARD RODER, OF ZEULENROD A/THURINGEN, GERMANY, ASSIGNOR TO CARL KNEUSEL, OF ZEULENROD A/THURINGEN, GERMANY.

CAN-END-FOLDING MACHINE.

Application filed December 24, 1925, Serial No. 77,636, and in Germany October 20, 1924.

The object of the present invention is a driving gear for a folding tool for closing machines, which are used for closing non-circular cans.

5 The essential feature of the novel device consists in that the positive motion of the guiding rollers with their supports produced during the working process by the rolling or devolving action of the noncircular can is used for performing the work of folding and that by this positive motion of the guiding rollers and its supports a feeding motion is imparted to the throwing or lifting curve, said feeding motion being 10 adjustable by means of a stop.

Through this condition or operation the automatic feeding motion of the folding rollers for forming the fold is produced directly at the supports of the folding- and 20 guiding-rollers, the hitherto necessary driving members of the folding-levers operated by the driving shaft through the machine are being obviated, and an adjustment to a greater or smaller number of can revolutions 25 for one single working operation is made possible and a more simple and easier working is obtained.

In the drawing one form of embodiment 30 of a folding machine according to the two-lever system (first- and final or finishing roller) is shown.

In the drawing—

Fig. 1 is a side elevation of a complete machine,

Fig. 2 is a side view of the arrangement of the tools,

Fig. 3 is a ground-plan of a disposition of the tools with folding-roller-lever in the initial position previous to placing a can into the machine.

Fig. 4 is a side-view of the tool-disposition with folding-roller-lever in initial position prior to putting in a can.

Fig. 5 is a plan-view of a tool-arrangement with folding-roller-lever in advanced position after several revolutions of spindle during operation.

In these drawings *a* denotes a friction coupling operated by the foot-pedal *c* and forming a coupling-connection between the driving pulley and the working-spindle of the machine, which connection is preserved also in case the foot-pedal is let go,

by means of a lever *w* in the well-known manner, said lever *w* being provided with a notch for the purpose. *b* and *c* are the two bottom disks, between which the can to be folded is placed and held; *d* is the guiding cam corresponding to the noncircular shape of the can and rigidly connected to the upper bottom-disk; *e* denotes the guide-roller-lever arranged to oscillate on a pivot-pin *f*, which is provided at the body of the machine. Said lever *e* carries at one end the guiding roller *g* which is positively guided in a slot in the guiding-cam *d*, and which slot conforms to the shape of the cam. The folding-roller-lever *i* is carried by the guiding-roller-lever *e* and is mounted on a pivot *h*. At the other end of the lever *e* a pawl-lever *k* is provided and is pivoted at *m* and provided with a pawl *l*. The folding-roller-lever *i* hereinbefore mentioned carries at one end the folding roller *n* and at the other end a carrying roller *o*, which bears against a lifting-cam *p*. This lifting cam *p* has connected to it a ratchet-wheel *q*, which is engaged by the pawl *l*. Said ratchet wheel and cam are free to revolve on the pivoting-pin *f* of the lever *e*, they are, however, connected with the guiding roller lever *e* by means of a key-brake *r* so that when the guiding roller lever *e* is oscillating around the pivoting pin *f* in a direction away from the working-spindle of the machine, the lifting cam *p* and the ratchet-wheel *q* are caused to revolve around *f*, as they are taken along by the key-brake *r*. They do not, therefore, change their position in regard to the guiding roller lever *e*, but at an oscillating movement of the guide roller lever *e* in the opposite direction the ratchet-lever *k* will strike against the adjustable stop *s* fixed to the body of the machine turn on its pivot arm, and cause the pawl *l* to move the ratchet-wheel *q*, and hence also the lifting cam *p* through a rotary movement around the pin *f* accelerated in relation to the guide roller lever *e*, and change the position of said cam in relation to the guide roller lever *e*. As a result, the carrying roller *o* of the folding roller lever *i* oscillating with the guide roller lever *e* will rise, to a higher point of the rising branch of the lifting cam *p*. Hence the distance between the carrying roller *o* and the oscillating axle *f* will

be increased and the folding roller n will approach the bottom disk b as a consequence of the double-arm ratio of leverage at the folding roller lever i . This train of movements repeats itself at every oscillating movement of the guide roller lever e caused by the revolution of the guiding cam d , and in this the above mentioned ratchet wheel q with the pawl l , and assisted by the key-brake r will operate in the manner of a ratchet, and will cause the lifting cam p to revolve around its axle f intermittently. Hence the folding roller n will gradually approach the bottom disk and if a can has been put in place, will perform the folding work. As soon as this is finished, i. e. if the carrying roller o has passed the highest point of the lifting cam, the carrying roller will run along the declining branch of the cam by action of the tension spring t , and the folding roller n will move away from the bottom disk. A stopping-pin u is provided on the lifting cam p , which will throw out of action, by means of the angle-lever v and lever w , the friction coupling a and thereby will stop the machine. The said stop s is adjustable so as to produce, by acting sooner or later on the ratchet-lever k , a greater or less advance of the ratchet-pawl l , a more rapid or slower turning of the lifting cam p and, consequently a longer or shorter duration of the folding operation, and hence make adjustable to different numbers of full turns the can-revolution speed per one folding operation.

The same train of operations and movements, as above described for the first or preparing folding roller, occurs in a similar way in the case of the finishing folding roller, in which case, however, the folding operations of both rollers occurs in the corresponding sequence during one revolution of the lifting cams only.

In the same manner this mode of driving may be used also with folding machines with slides or supports or carriages serving as folding roller carriers in contra-distinction to the example given here and relating to a machine with levers as folding-roller-carriers, or machines with rotating folding tools and stationary guiding cam and can.

The operation is as follows:

The can to be folded is placed on the lower bottom disk c . By depressing the foot-lever c' the can together with the lower bottom disk c is lifted and jammed tight between the upper and lower bottom disks b and c ; at the same time the friction coupling a is made to operate and the working spindle of the machine and with it the guiding cam d and the can to be folded are thereby made to rotate. Hereby the oscillating movements of the folding roller lever e are started and consequent upon this, by means of the ratchet lever k with pawl l and stop s as de-

scribed above, the intermittent rotary movement of the lifting cam p and consequently the folding operations of the folding roller n . As soon as the lifting cam p has described a complete revolution around its axle f , the stop-pin u fixed to it will strike the angle lever v . Hereby the latter is moved around its pivoting point z , the lever w is lifted from out of the locking position, the notch having caught on throwing the machine into operation, and now the friction coupling a is released and the machine is stopped. At the same time the foot-pedal, which had remained in its depressed position during work, goes back into its raised initial position of rest, and the lower bottom disk c lowers down with the folded can into its initial position.

I claim:

1. In a can end folding machine, in combination with bottom discs and non-circular guiding cam fast to one of the discs, a guide roller lever pivotally mounted at a point intermediate its ends and provided with a guiding roller which is guided by said cam, a pawl operating lever pivotally mounted at a point intermediate its ends at the other end of the guide roller lever, said pawl operating lever being provided at its inner end with a pawl, a stop element arranged in the path of movement of the outward end of said pawl operating lever, a folding roller lever pivotally mounted at a point intermediate its ends on said guide roller lever and provided at its outer end with a folding roller and at its inner end with a carrying roller, a spring active to move the guide roller end of said guide roller lever outwardly, a lifting cam mounted on the pivot of the guide roller lever and against which said carrying roller of said folding roller lever bears, and a ratchet wheel fixed to said lifting cam and engaged by said pawl for partial rotation of said lifting cam and said ratchet wheel when said pawl operating lever engages said stop.

2. In a can end folding machine, in combination with bottom discs and non-circular guiding cam fast to one of the discs, a guide roller lever pivotally mounted at a point intermediate its ends and provided with a guiding roller which is guided by said cam, a pawl operating lever pivotally mounted at a point intermediate its ends at the other end of the guide roller lever, said pawl operating lever being provided at its inner end with a pawl, a stop element arranged in the path of movement of the outward end of said pawl operating lever, a folding roller lever pivotally mounted at a point intermediate its ends on said guide roller lever and provided at its outer end with a folding roller and at its inner end with a carrying roller, a spring active to move the guide roller end of said guide roller lever

er lever outwardly, a lifting cam mounted on the pivot of the guide roller lever and against which said carrying roller of said folding roller lever bears, and a ratchet wheel fixed to said lifting cam and engaged by said pawl for partial rotation of said lifting cam and said ratchet wheel when

said pawl operating lever engages said stop, the said stop being adjustable to vary the extent of movement of said pawl operating lever.

In testimony whereof I affixed my signature.

RICHARD RODER.
